UNITED STATES PATENT OFFICE.

EUGENE A. KUEN, OF CINCINNATI, OHIO, ASSIGNOR TO THE THOS. J. CORCORAN LAMP COMPANY, OF CINCINNATI, OHIO, A CORPORATION OF OHIO.

VEHICLE LAMP.

Application filed June 5, 1920. Serial No. 386,741.

To all whom it may concern:

Be it known that I, EUGENE A. KUEN, a citizen of the United States, residing at Cincinnati, in the county of Hamilton and 5 State of Ohio, have invented certain new and useful Improvements in Vehicle Lamps, of which the following is a specification.

My invention relates to vehicle electric lamps, especially such as are used as head-lights on automobiles and other vehicles, 10 as so-called spot-lights for vehicles, and for other purposes.

It is the object of my invention to provide new and improved means whereby to locate 15 the reflector in an electric lamp of the character mentioned; further, to provide new and improved means whereby to cause pressure upon the reflector; further, to provide novel means whereby to secure a closure in 20 position in a lamp of the character mentioned; further, to provide new and improved means whereby to relatively position the body, the reflector and the closure, and to cause pressure between the same; 25 further, to provide new and improved means whereby to locate the light transmitting plate in the ring-member of the closure; and, further, to provide new and improved means to seal the space between 30 the light transmitting plates and the reflector and to cushion the light transmitting plate and reflector.

The invention will be further readily understood from the following description and 35 claims, and from the drawings, in which latter:

Fig. 1 is a perspective view of the body of my improved device.

Fig. 2 is a similar view, with the reflector 40 in the body, partly broken away.

Fig. 3 is a perspective view of the closure of my improved device.

Fig. 4 is a detail in front end elevation showing the reflector in the body but not 45 rotated.

Fig. 5 is a similar view, with the reflector partly rotated.

Fig. 6 is a similar view, showing the closure in place.

Fig. 7 is a side elevation of a detail show-

ing the reflector in the body but not rotated.

Fig. 8 is a side elevation of a detail showing the reflector assembled in the body, and the closure placed on the body but not rotated. 55

Fig. 9 is a similar view of the parts in assembled relation.

Fig. 10 is an outside elevational detail of the closure.

Fig. 11 is an inside elevational detail of 60 the same; and,

Fig. 12 is a cross-section of the same, taken on the line 12—12 of Fig. 6.

My present invention is an improvement upon the device shown, described and claimed in Patent No. 1,334,762, issued to me under date of March 23, 1920, for fastening device for automobile lamp closure. 65

The invention is exemplified as applied to an electric lamp having a parabolic reflector 21. The body 22 of the lamp is preferably of usual parabolic form. Its front end is preferably provided with an annular wall 23, shown as a cylindrical flange. An annular bead 24 is preferably located at the rear end of this annular wall. A closure 25 is provided, exemplified as comprising a ring-member 26 having an annular wall 27, shown as a cylindrical flange, and a light transmitting plate 28. 70

Closing means for the lamp are located between the body and the closure, these closing means comprising springs and complemental contact-members, with which the body and the closure are respectively provided, the body in the present exemplification being provided with the springs and the closure with the complemental contact-members. Thus the annular wall of the body is provided with recesses 31. Springs 75

32 span the recesses. Pins 33 on the closure 80 coact with the springs for drawing the closure, the reflector and the body toward each other. A series of these closing means is provided, three of the same being shown. 85

The spring is preferably a plate spring exerting pressure in the direction of its width, and torsionally. 90

The respective ends of the spring are received in sockets 35, 36, which are struck 100

outwardly from the body of the wall 23, forming bulges 37, 38. The sockets are provided with slots 39, 40, projecting toward each other, through which tongues 41, 42, 5 formed at the respective ends of the spring, are received. The sockets are preferably wider than the tongues so as to permit pivotal shifting of the ends of the tongues in the direction of width of the spring when 10 the spring is flexed. The front walls of the slots form fulcrums on which the ends of the spring are fulcrumed during the flexing movement of the middle portion of the spring by the movement of the pin along the 15 spring while rotating the closure for locking the closure to the body. Shoulders 43, 44, on the spring coat with the walls of the sockets to position the spring endwise. The middle portion of the spring normally 20 lies in the plane of the wall 23 when unflexed by the pins.

The spring is provided with an inward bend 46 to form a recess for accommodating the pin to permit the pin to pass to the rear 25 edge of the spring when the closure is moved toward the body, which movement is instanced as parallel with the axis of the body or focal axis of the reflector. The rear edge of the spring is inclined rearwardly adjacent 30 to this bend for forming a wedge face 48 on which the pin rides for causing pressure between the closure, the reflector and the body. The rear edge of the spring is also provided with the forwardly projecting recess 49, 35 forming a shoulder 50 at the end of the wedge face of the spring, behind which the pin is adapted to be received when the closure, the reflector and the body are securely clamped together. The shoulder has a 40 comparatively abrupt incline acting to hold the pin in place during ordinary usage, but permitting reverse rotation of the closure by forceful action when it is desired to remove the closure.

45 The striking of the bulges 37, 38, outwardly form friction-relieving riding spots for the wall of the closure for relieving friction when rotating the closure, and the location of the ends of the springs outside the 50 annular wall of the body leaves the inner face of the annular wall free of obstruction for the ready reception and rotation of the reflector.

55 The body is provided with inwardly extending lips 53 which are shown struck inwardly from the rear walls of the recesses 31. Preferably larger lips 54 are also shown struck inwardly from the rear walls of said recesses. There is a pair of these lips 53, 54, 60 at each of the recesses for locating the reflector. The lips 53 and 54 are formed out of material between the ends of the recesses 31, which would otherwise be cut away to form the recesses, and are bent inwardly from the

65 rear walls of the recesses, making an exceptionally compact and economical structure. The lips 53 are located in axial direction slightly forward of the lips 54, the distance between them in lines parallel to the axis of the lamp being slightly less than the thickness of the flange 55 of the reflector. The 70 relative positions of the lips of the respective pairs of lips is such as to engage the respective forward and rear faces of this flange and hold the same firmly between 75 them for locating the reflector in the body.

The reflector is formed with said flange which, in the form shown, is bent outwardly from a rearwardly extending flange 56, which extends rearwardly from the front edge of the reflector for forming a reversely bent front end 57 on the reflector.

The flange 55 of the reflector is provided with recesses 58. One of the corners of each of these recesses, namely, the corner 59, 85 which moves toward the lips 53 when rotating the reflector for positioning of the reflector in the body, is bent slightly rearwardly, as shown in Figs. 4 and 7 so as to cause said walls to be readily received under the lips 53, when rotating the reflector. When the reflector is placed into the body of the lamp, its recesses 58 are brought into line with the inward bends 46 of the springs, 90 being also in line with the lips 53 which are in rear of said bends. The lips 54 preferably extend inwardly further than the lips 53. When the reflector is received in the body in the relation stated, the flange of the reflector rests on the lips 54, which form limits for 95 the inward movement of the reflector. Upon rotation of the reflector, the reflector rotates on the lips 54, and the corners 59 of the recesses 58 are received under the lips 53, the 100 rearwardly bent corners forming forwardly 105 extending wedge faces for wedging the flange of the reflector between the lips 53 and 54.

110 The light transmitting plate 28, exemplified as of glass, is located in the ring-member, preferably against the rear end of a rearwardly extending flange 61, which, in the exemplification, forms an inner annular channel 62 in the ring-member. A cushion 64 is at the inner face of the light transmitting plate. This cushion is exemplified as a flat annular cushion and may for instance be a strip or ring of card board, or other cushioning material adapted to be arranged in annular form. This cushion is 115 preferably held in the ring-member. Thus clips 65 are located in the ring-member and have fingers 66 which extend rearwardly and have inwardly bent ends forming lips 67 in rear of the cushion, with the cushion located between the light transmitting plate and the lips, so as to cushion the lips and thereby avoid fracture or damage to the 120 125

edge of the light transmitting plate. The cushion also acts as a cushioning means between the light transmitting plate and the forward end of the reflector, movable with 5 the closure.

The clip 65 is preferably formed of a single piece of sheet metal and comprises a body-portion 68, provided with a bend 69, extending into the channel 62 of the closure, 10 and with the fingers 66. The clip is provided with a hole 70, the annular wall of the closure being provided with a mating hole 71. A rivet is received through these holes, the head 72 of the rivet being at the outside 15 of the closure. The inner end of the rivet is thereupon upset upon the clip to form the inner shoulder 73, for rigidly securing the wall, the clip and the rivet together, the inner end of the rivet forming the pin 33 of 20 the closure which coacts with the spring 32.

When the closure is applied to the body, and the pins have passed through the recesses formed by the bends 46 in the springs, as hereinbefore explained, the reflector having 25 been placed in the body, a relative rotation between the closure and the body will cause movement of the pins along the rear edges or wedge faces of the springs, thereby drawing the closure and the body toward 30 one another, and causing pressure upon the cushion 64, located between the light transmitting plate and the forward end of the reflector. The outwardly struck bulges 37, 38, which form the sockets 35, 36, receiving 35 the ends of the springs, form centering means for the ring-member of the closure, the inner face of the annular wall of the closure riding on these bulges and thereby centering the ring-member with relation to the 40 body and reducing friction between the body and the ring-member during rotation.

The relative rotation between the closure and the body, by action of the pins, causes flexing of the springs in the plane of the 45 widths of the springs, and also radial flexure of the springs with relation to the body and reflector, for causing torsional movement of the springs to exert radial pressures by the springs upon the closure to aid in centering 50 the closure on the body, and exert lateral pressure between the annular wall of the body and the annular wall of the closure to aid in firmly securing the closure to the body and the reflector in the body and avoid 55 vibration or rattling of the parts.

The present invention also provides means, by coaction between the closure and reflector, and between the reflector and the body, for firmly securing the reflector in the body, and, by means of the cushion, sealing the 60 space between the light transmitting plate and the reflector, for preventing the entrance of dust and moisture into said space. The annular bead at the inner end of the an-

nular wall of the body is arranged to coact 65 with the rear edge of the annular wall of the closure to close the space between the rear end of the closure and the body.

A suitable electric lamp bulb 75 may be provided in the rear end of the reflector, 70 and may be suitably held in place or adjusted, and have suitable electrical connections therewith in any suitable or well-known manner.

Having thus fully described my invention, 75 what I claim as new, and desire to secure by Letters Patent, is:

1. In a lamp of the character described, the combination of a body having a forwardly projecting annular wall, a reflector 80 in said body, and a closure comprising a ring-member and a light transmitting plate, said ring-member provided with a rearwardly extending annular wall located substantially concentric about said annular wall 85 of said body and spaced radially therefrom, coengaging means between said walls comprising leaf-springs and complemental contact-members, one of said walls provided with seats projecting into said space between said walls, said seats arranged for receiving said leaf-springs to locate said leaf-springs, and said seats forming centering means between said walls by contact of the other of said walls therewith, whereby to locate said closure concentrically with 90 relation to said body.

2. In a lamp of the character described, the combination of a body, a reflector therein, a closure, said body and closure provided with substantially concentric lapping walls normally slightly spaced apart, said body provided with an annular bead at the rear end of said wall of said body, coengaging 100 means between said walls comprising leaf-springs and complemental contact-members, and seats between said walls for said leaf-springs projecting into the space between said walls, and the rear end of said outer wall received over the outer periphery of said bead and said seats forming separating centering means between said walls and between said rear end of said outer wall and said bead.

3. In a vehicle lamp, the combination of 115 a body, springs at the forward end of said body, the widths whereof extend from front to rear, said springs provided with inwardly extending bends to form outer recesses, said body provided with inwardly extending pairs of lips, one of the lips of each of said pairs of lips coincident in position in directions parallel with the axis of said body with said outer recesses, a reflector having a radially outwardly extending flange provided with recesses arranged to pass said inward bends and said one of said lips by movement of said reflector substantially 120 125

parallel with the axis of said reflector and body, said flange and lips having a wedge-face between them whereby said flange is located between the lips of said respective pairs of lips with wedge-like pressure by said flange upon said lips upon rotation between said reflector and said body, and a closure provided with contact-parts complementary to said springs received past said inward bends and under said springs and for-

ward of said lips for causing pressure between said closure and said reflector and body.

In testimony whereof, I have hereunto signed my name in the presence of two subscribing witnesses.

EUGENE A. KUEN.

In presence of:

JAMES J. FITZPATRICK,
DELMA WERNING.
